[57] CLAIM

The ornamental design for an attachable truck mat, as shown and described.

DESCRIPTION

FIG. 1 is a perspective view of an attachable truck mat, showing my new design, it being understood that the broken lines are for illustrative purposes only and form no part of the claimed design;

FIG. 2 is a left side elevational view of the mat with the right side elevational view being a mirror image thereof;

FIG. 3 is a bottom plan view thereof;

FIG. 4 is a rear elevational view thereof;

FIG. 5 is a top plan view thereof; and,

FIG. 6 is a front elevational view thereof.
